UNITED STATES PATENT OFFICE

133,181

DESIGN FOR A CLOCK FRAME OR SIMILAR ARTICLE

Howard O. Johnston and Roy E. Luikart,
Detroit, Mich.

Application December 31, 1941, Serial No. 104,948

Term of patent 3½ years

To all whom it may concern:

Be it known that we, Howard O. Johnston and Roy E. Luikart, citizens of the United States, residing at Detroit, county of Wayne, and State of Michigan, have jointly invented a new, original, and ornamental Design for a Clock Frame or Similar Article, of which the following is a specification, reference being made to the accompanying drawing, forming part thereof.

Fig. 1 is a front view of a clock frame or similar article, showing our new design.

Fig. 2 is a side elevation thereof.

We claim:

The ornamental design for a clock frame or similar article, as shown.

HOWARD O. JOHNSTON.
ROY E. LUIKART,
